READOUT HEAD FOR A SONAR SYSTEM OR SIMILAR ARTICLE

David S. Wyse and James E. Kienker, Dayton, Ohio, assignors to Projects Unlimited, Inc., Dayton, Ohio, a corporation of Ohio

Filed Dec. 28, 1964, Ser. No. 83,195

Term of patent 14 years

(Cl. D26—5)

FIG-1

FIG-2

FIG-3

FIG-4

FIG-5

FIG-6

FIG-7

FIG. 1 is a left side, top and front perspective view of a readout head for a sonar system or similar article, showing our new design;

FIG. 2 is a front elevational view;

FIG. 3 is a right side elevational view;

FIG. 4 is a left side elevational view;

FIG. 5 is a rear elevational view;

FIG. 6 is a top plan view; and

FIG. 7 is a bottom plan view thereof.

The dominant features of our new design are shown in solid lines in the drawing.

FIGS. 1 and 2 have been diagonally lined to indicate transparency.

We claim:

The ornamental design for a readout head for a sonar system or similar article, substantially as shown and described.
